(57) **CLAIM**

The ornamental design for a display mount, as shown and described.

DESCRIPTION

FIG. 1 is a first isometric view of a display mount.

FIG. 2 is a front view of the display mount of FIG. 1.

FIG. 3 is a rear view of the display mount of FIG. 1.

FIG. 4 is a top view of the display mount of FIG. 1.

FIG. 5 is a bottom view of the display mount of FIG. 1. FIG. 6 is a first side view of the display mount of FIG. 1; and,

FIG. 7 is a second side view of the display mount of FIG. 1. The broken lines depict portions of the display mount and form no part of the claimed design.

1 Claim, 7 Drawing Sheets
